UNITED STATES PATENT OFFICE.

SAMUEL KRUGER, OF NEW YORK, N. Y.

SAFETY SPOOL-HOLDER FOR SEWING-MACHINES.

1,142,183.

Specification of Letters Patent. Patented June 8, 1915.

Application filed September 14, 1914. Serial No. 861,509.

To all whom it may concern:

Be it known that I, SAMUEL KRUGER, a citizen of the United States, and residing at New York, in the county of New York and 5 State of New York, have invented certain new and useful Improvements in Safety Spool-Holders for Sewing-Machines, of which the following is a specification, such as will enable those skilled in the art to 10 which it appertains to make and use the same.

This invention relates to holders for the thread spools of sewing machines and the object thereof is to provide an improved design 15 of this class designed for use in manufacturing establishments, and to prevent the theft of the spools of thread.

The invention is fully disclosed in the following specification, of which the accompanying drawing forms a part, in which the separate parts of my improvement are designated by suitable reference characters in each of the views, and in which:—

Figure 1 is a sectional view showing my 25 improved spool holder secured to the table of a sewing machine; Fig. 2 a side view of the spool holder detached; Fig. 3 a perspective view of a spring arm which I employ, and Fig. 4 a cross section on the line 4—4 30 of Fig. 2.

In the drawing forming part of this specification, I have shown at *a* the table of a sewing machine, and at *b* a spool of thread of the class usually employed in manufacturing establishments. In the construction shown, the spool *b* is without the ordinary end heads but said spool may be provided with the usual end heads if desired.

In the practice of my invention, I have 40 provided a spool holder comprising a standard *c* having a flat base *c*² which is secured to the table *a* by screws *c*³ or in any desired manner.

The standard *c* is provided with a head *c*⁴ 45 at the bottom of which is an abrupt annular shoulder *c*⁵, this construction being formed by cutting out the standard *c* circumferentially from the head *c*⁴ downwardly, whereby the body portion of the standard below 50 the head is tapered as shown at *c*⁶.

In one side of the spool *b* is a longitudinal slot *b*³ at the bottom of which is an L-shaped groove *b*⁴ which communicates therewith, and I also provide a spring arm *d* which is 55 formed to fit in the slot *b*³ and is provided at one end with an inwardly directed lug or

projection *d*², and at the opposite end with an L-shaped handle portion *d*³ which is adapted to fit in the L-shaped groove *b*⁴.

The spring arm *d* is curved slightly in the plane thereof and when placed in position with the part *d*⁴ in the slot *b*³, and the L-shaped part *d*³ in the L-shaped groove *b*⁴, the thread *e* when wound on the spool, will hold the spring arm *d* in the slot *b*³ and the L-shaped part *d*³ of said arm in the groove *b*⁴, and the end part *d*⁴ of the arm *d* will project into the spool and the lug or projection *d*² will operate in connection with the head *c*⁴ of the standard *c* to hold the spool on said standard, and said spool cannot be taken off from the standard until all the thread *e* is unwound from the spool, when the spring arm *d* will drop out and the spool may be removed from the standard and another spool with its spring arm in position and with the thread *e* wound thereon, may be passed down over the standard as will be readily understood.

The head *c*⁴ of the standard *c* is beveled on its outer end so as to permit the passing of the spool downwardly over said standard, but when the spool is fully in position, the arm *b*³ or the lug or projection *d*² thereof will catch under the head of the standard as shown in Fig. 1, and lock the spool thereon.

My invention is not limited to the use of a spring arm loosely connected with the spool, or held in connection therewith, by the thread only, and any sort of a spring arm that is thrown into operative position by the thread on the spool will answer all requirements, and while I have shown and described the construction of the standard, spool and spring which I prefer, it will be understood that changes therein and modifications thereof may be made, within the scope of the appended claims, without departing from the spirit of my invention or sacrificing its advantages.

Having fully described my invention what I claim as new and desire to secure by Letters Patent is:—

1. A thread spool holder adapted to be secured to the table of a sewing machine and comprising a standard and a thread spool provided with a spring which is adapted to engage said standard and to lock the spool thereon, said spring being held in operative position by the thread wound on the spool.

2. A thread spool holder adapted to be

- secured to the table of a sewing machine and comprising a standard, and a thread spool provided with a spring which is adapted to engage said standard, said spring being held 5 in operative position by the thread wound on the spool; and being released when the thread is unwound from the spool.
3. A thread spool holder adapted to be secured to the table of a sewing machine and 10 comprising a standard on which the spool is loosely mounted, said standard being provided with a part adapted to be engaged by a spring, and a spring mounted in said spool and adapted to engage said part, said spring 15 being held in operative position by the thread wound on said spool.

4. A thread spool comprising a standard provided with a head on which the spool is adapted to be placed, said spool being provided with a spring lock device adapted to engage said head and which is held in operative position by the thread wound on the spool. 20

In testimony that I claim the foregoing as my invention I have signed my name in 25 presence of the subscribing witnesses this 12th day of September, 1914.

SAMUEL KRUGER.
